RESTAURANT BUILDING

Rocco E. Marino, 4747 Collins Ave.,
Miami Beach, Fla. 33140

Filed Nov. 29, 1968, Ser. No. 14,726

Term of patent 14 years

Int. Cl. D25—04

U.S. Cl. D13—1

FIGURE 1 is a front elevational view of a restaurant building showing my new design.

FIGURE 2 is a rear elevational view.

FIGURES 3 and 4 are side elevational views.

FIGURE 5 is a plan view.

I claim:

The ornamental design for a restaurant building, substantially as shown.
